CLAIM

The ornamental design for sausage, as shown and described:

DESCRIPTION

FIG. 1 is a top front left end perspective view of a sausage, showing my new design;

FIG. 2 is a front elevational view thereof, the top plan, bottom plan and rear elevational views being mirror images thereof;

FIG. 3 is a left end elevational view thereof; and

FIG. 4 is a right end elevational view thereof.

The top, bottom, and the side not shown are the same as the side illustrated.

FIG. 1

FIG. 2

FIG. 3

FIG. 4
